UNITED STATES PATENT OFFICE.

SIGMUND HOROWITZ, OF LEMBERG, AUSTRIA-HUNGARY.

GASIFICATION APPARATUS.

1,105,975.

Specification of Letters Patent.

Patented Aug. 4, 1914.

Application filed June 20, 1914. Serial No. 846,254.

To all whom it may concern:

Be it known that I, SIGMUND HOROWITZ, a subject of the Emperor of Austria-Hungary, residing at Lemberg, Austria-Hungary, have 5 invented a new and useful Improvement in Gasification Apparatus, of which the following is a specification.

My invention relates to gasification apparatus, used for instance in connection with 10 combustion engines and has for its object to bring about a quick gasification of the fuel, thus permitting the use of not easily volatile fuels, such as kercsene. Owing to the slow 15 gasification of these fuels, all attempts herebefore to use the same for operating combustion engines, for instance of automobiles, have been unsatisfactory.

A further object of my invention is to so 20 construct the fuel feeding device that it can readily be operated and regulated, even from a point relatively far away from the gasification apparatus proper, so that for instance, the driver of an automobile, from his seat in the front of his car, may put into 25 operation, stop and regulate the flow of the fuel into the gasification apparatus of the combustion engine of his car.

My invention will be fully described hereinafter and the features of novelty will be 30 pointed out in the appended claim.

My invention is illustrated in the annexed drawing which shows a gasification apparatus, in longitudinal section, such as may be used in connection with the combustion engine of an automobile.

As illustrated in the drawing 1 designates the casing, screw-threaded at the bottom to receive the screws 2 by which the bottom plate 3 of the casing is fastened thereto. 40 The interior of said casing is divided into an inner gas chamber *b* within the closed partition wall 4, and an outer air chamber *a* between the casing 1 and the said partition wall 4, which outer chamber connects with 45 the atmosphere through holes in the said casing 1, which holes may be partially or completely closed by the slide valve 12. Said partition wall 4, which as illustrated is of cylindrical shape, is preferably formed by a 50 continuous pipe coil in which the several pipe lengths are adjacent to each other, while the ends of said pipe coil pass through said bottom plate 3 and connect with the exhaust pipes of the engine. Within said inner chamber *b* a plate 5 is provided above the

bottom plate 3 of the casing. The upper side of said plate 5, as shown in the drawing, forms a trough for receiving finely divided inert material such as sand, gravel or the like 6', any suitable means being provided if desired for preventing the spilling of the said inert material. At the underside of said plate 5 is provided a heating means 6, for instance an electrical heating body fed by the storage battery used in connection with the lighting system of the car. Above the plate 5, in the cover of the casing 1, is located the feeding device for the liquid fuel. This device, as illustrated, consists of the valve pin 9, visible through the sight glass 8, 70 and connected with a valve cone 7 which may be raised and lowered by means of the valve spindle 11 axially adjustable within the valve body 10, the latter being suitably connected with a source of fuel supply. By operating this valve spindle 11 either directly or by means of an intermediary member readily accessible from the driver's seat, the opening of the nozzle of the valve, and thereby the flow of the fuel through the valve 80 into the gasification chamber can be easily adjusted.

The cover of the casing 1 has on its underside an inwardly projecting flange 13 which extends close to the upper end of the partition wall 4, and forms a hood-like cover for the inner chamber *b*. The outlet pipe 14 may connect either directly with the explosion chamber of the engine or with the gas mixing chamber of an auxiliary carburetor, 85 which may be of any desired form, for instance of a spray-nozzle carburetor.

In operation a slight raising of the spindle 11 will cause the fuel, for instance kerosene, slowly to drop from the needle 9 through 95 the inner chamber *b* upon the material 6' in the trough of the plate 5. As filling material for the trough any kind of an inert heat retaining material, such as sand, gravel, quartz or other ceramic substances, in a 100 finely divided condition, may be used. It will be apparent that each drop of the fuel in passing through the chamber *b* becomes heated and in this heated condition impacts against this filling material 6'. In this way 105 each drop of the heated fuel will be split up into minute particles; and as said filling material has been previously heated by means of the electrical heating device, 6, the gasification of the fuel will be very rapid, 110

especially as, in the example shown, the impact material 6' is in a finely divided condition and thus exposes a maximum of fuel surface. The gases thus generated will rise 5 within the inner chamber b. A condensation of the fuel gases in said chamber is prevented by having the hot exhaust gases pass through the pipe coil constituting the partition wall 4. For the purpose of having the 10 said partition wall 4 heated before the gasification commences in my improved apparatus, heat must be supplied to said wall from an outside source. This may preferably be done by having the engine also provided 15 with a small ordinary gasoline carburetor for starting the engine, which carburetor may be shut off as soon as the exhaust gases passing through the pipe coil 4 have sufficiently raised the temperature of the interior chamber b to prevent a condensation of the kerosene gases rising within the same. The rising gases on their way out through the exhaust pipe 14 will suck air through the 20 slide valve 12 and the outer chamber a. In passing through said chamber a the air will 25 be heated as a result of the heat given off by the hot pipe coil 4. The thus preheated air mixes with the also preheated gases above the interior chamber b in the mixing chamber 30 formed by the flange 13 and the mixture of gas and air will pass off through the outlet pipe 14 into the explosion chamber of the engine. The amount of air sucked through the holes in the casing 1 can be 35 readily regulated by operating the slide valve 12, and as the flow of the fuel is likewise readily controlled by the operation of the spindle 11 of the valve cone 7, it is apparent that the proportion of air and fuel 40 gases in the mixing chamber above the inner chamber b can be easily so adjusted that the mixture passing off through the outlet pipe

14 constitutes a gas and air mixture of the desired explosive properties.

If desired the valve spindle 11 and consequently the valve cone 7 and valve pin 9 may be set to secure the necessary flow of fuel from the valve body 10 and the supply of fuel to the latter controlled by a suitable valve located in the connection between said valve body 10 and the fuel source.

Various other changes in the specific form of my gasification apparatus shown and described, for instance in the shape of the plate 5 or the construction of the feed valve may 55 be made within the scope of the claims without departing from the spirit of my invention.

I claim:

In a gasification apparatus, the combination of a casing adapted for connection with the explosive chamber of an internal combustion engine and provided with an air inlet and a mixing chamber, a heating coil within said casing forming a gasification 60 chamber in communication with said mixing chamber, said coil being adapted to be connected with the engine exhaust, a support located in the lower portion of said gasification chamber, finely divided inert material 65 carried by said support, electrical means for heating said support and said inert material, a fuel inlet located above said inert material, whereby liquid fuel is dropped upon the latter, and means for regulating the flow 70 of fuel.

In testimony whereof, I have hereunto set my hand in the presence of two subscribing witnesses.

SIGMUND HOROWITZ.
